US0D1091572S

(12) **United States Design Patent** (10) Patent No.: **US D1,091,572 S**
 (45) Date of Patent: ** Sep. 2, 2025

(54) **DISPLAY SCREEN WITH GRAPHICAL USER INTERFACE**

(71) Applicant: **Venugopal Ramakanthan**, Dickinson, TX (US)

(72) Inventor: **Venugopal Ramakanthan**, Dickinson, TX (US)

(**) Term: **15 Years**

(21) Appl. No.: **29/892,402**

(22) Filed: **May 17, 2023**

(51) LOC (15) Cl. **14-04**

(52) U.S. Cl.

USPC **D14/485**

(58) **Field of Classification Search**

USPC **D14/485-495**

CPC G06F 3/048; G06F 3/0482; G06F 3/04817; H04M 1/724-72484

Primary Examiner — Rachel A. Voorhies

(57) **CLAIM**

The ornamental design for a display screen with graphical user interface, substantially as shown and described.

DESCRIPTION

The sole FIGURE is a front view of a display screen with graphical user interface.

The outermost broken line rectangle illustrates a display screen and forms no part of the claimed design.

1 Claim, 1 Drawing Sheet
